VENDING MACHINE

Harold L. Smith, Columbus, Ohio, assignor to Ideal Dispenser Company, Columbus, Ohio, a corporation of Ohio

Filed Oct. 7, 1964, Ser. No. 82,076

Term of patent 14 years

(Cl. D52—3)

FIG. 1

FIG. 3FIG. 4

FIG. 1 is a front perspective view of the vending machine showing my new design;

FIG. 2 is a side elevational view of the vending machine;

FIG. 3 is a top plan view of the vending machine; and

FIG. 4 is a front elevational view of the vending machine.

The undisclosed side of the vending machine is substantially the same in appearance as the side shown, and the rear is flat and plain.

I claim:

The ornamental design for a vending machine, as shown and described.
